Primary Examiner — Kevin Rudzinski*Assistant Examiner* — Sean D Lough(74) *Attorney, Agent, or Firm* — Leason Ellis LLP(57) **CLAIM**

The ornamental design for a catalyst basket, as shown and described.

DESCRIPTION

FIG. 1 is a perspective view of a catalyst basket showing our new design in a first orientation;

FIG. 2 is an elevation view of FIG. 1;

FIG. 3 is a top plan view of FIG. 1;

FIG. 4 is a bottom plan view of FIG. 1;

FIG. 5 is a close-up perspective view of the central aperture of the design of FIG. 1; and,

FIG. 6 is a perspective view of FIG. 1 with the mesh of the top, bottom, and outer periphery hidden solely for the purpose of better illustrating the internal structure of the catalyst basket, which is at least partially visible through the mesh.

The broken lines shown in the Figures of screws, rivets, and reinforcements, as well as their respective placement, size and configuration, illustrate the environment only and form no part of the claimed design.
